UNITED STATES PATENT OFFICE

2,010,716

ELECTRIC SWITCH GEAR

John Melville Goodall, High Barnet, and Eugene David Regis, Cricklewood, England, assignors to General Electric Company, a corporation of New York

Application November 28, 1934, Serial No. 755,224
In Great Britain November 24, 1933

5 Claims. (Cl. 175—298)

The present invention relates to the selection of alternative busbars in enclosed or metal-clad high tension electric switchgear.

The usual method employed for selecting busbars in metal-clad switchgear is to provide a selecting switch comprising a pivoted lever adapted to be operated to one of two or more alternative positions for the purpose of engaging spaced contacts arranged in the plane of movement of the lever, which contacts are adapted to be connected to the alternative busbars, known generally as main and auxiliary busbars, usually through isolating contacts at which disconnection is effected by the movement of a movable portion 15 of the gear with relation to the fixed portion thereof.

According to the present invention selection is effected by rotation about its axis of a member carrying contact surfaces angularly spaced with 20 respect to the axis of the member and adapted to engage stationary contacts associated with the alternative busbars.

The invention is particularly applicable to circuit breakers having only a single break per 25 phase, and in carrying the invention into effect in connection with such a circuit breaker having a movable contact rod adapted to engage a stationary contact located in axial alignment with the movable contact rod, we arrange for the stationary contact to be mounted in such a manner 30 that it is capable of rotation about its axis and is carried by a member having contacts which are separated from one another axially on the member and are arranged at different angular positions with regard to said axis. For the selection 35 of the alternative busbars the said member carrying the stationary contact is rotated about its axis whereby the spaced contacts can be brought separately into contact with stationary 40 contacts connected to the busbars to be selected.

The single figure of the accompanying drawing is an elevational view, partly in section, illustrating an arrangement embodying the invention for 45 use in connection with a duplicate busbar metal-clad switchgear.

As illustrated in the drawing, the combined circuit breaker and busbar selection device is contained within an elongated casing 1, carrying 50 at its upper end a movable contact rod 2 actuated to open and closed positions by moving it axially through suitable mechanism contained in the upper part of the casing at 3. Supported from the casing in axial alignment are three plug-type 55 contacts 4, 5, 6. These contacts are adapted to

engage with correspondingly located contacts on a fixed portion of the gear which contains the busbars. When the circuit breaker is in position on the fixed portion of the gear, contact 4 will engage a busbar connected to a feeder, while contacts 5 and 6 will be in connection with duplicate or main and auxiliary busbars providing alternative sources of supply to which the feeder can be connected through the circuit breaker. Plug-type contact 4 terminates at its 10 inner end within the casing 1 in a contact member providing slidable engagement with the contact rod 2.

The fixed contact of the breaker with which the contact rod 2 is adapted to engage is contained within an explosion pot indicated at 7. This explosion pot may be arranged to embody in known form an arc control device of special design, or it may be an ordinary well-known form of explosion pot. 20

The explosion pot is mounted on a rotatable member indicated generally at 8. This member is mounted upon insulators 9 upon a gear wheel 10 supported between flanges formed as part of the casing so that it is capable of rotation within 25 the flanges. This rotation is effected by means of a second gear wheel 11 and operating shaft 12. The explosion pot 7 is carried at the upper end of the member 8, which also comprises contact elements 13 and 14 which are arranged on 30 cranked parts of the member 8.

These contact elements 13 and 14 are spaced axially along the rotatable member 8 and are also angularly displaced with reference to the axis of the member 8 so that on rotation of the latter 35 either contact 13 can be brought into engagement with a contact 15 which is carried on the inner end of the plug-type contact 5 or contact element 14 can be brought into engagement with a corresponding contact 16 on the inner end of 40 contact 6.

Thus, by rotating the member 8 a circuit can be completed when the breaker is closed from either of the duplicate busbars to the feeder connected to contact 4, as desired. Suitable 45 interlocking devices of any well known type are provided for ensuring that selection is not carried out when the breaker is in the closed position.

The casing 1 may be provided with insulating 50 linings 17 to protect the inner wall of the casing from the effects of the arc formed during the circuit breaking operation and is also provided with an inspection cover 18 by which access may be had to the explosion pot 7. Normally this in- 55

spection cover should not be removed except when the breaker is isolated from the fixed portion of the gear, by being withdrawn therefrom using a suitable carriage for the purpose. The casing 1
5 is customarily filled with oil to the level indicated at 19.

It should be understood that our invention is not limited to specific details of construction and arrangement thereof herein illustrated, and that 10 changes and modifications may occur to one skilled in the art without departing from the spirit of our invention.

What we claim as new and desire to secure by Letters Patent of the United States is:—

- 15 1. A combined bus-bar selection device and circuit breaker for use with high tension metal clad switchgear comprising a casing, relatively fixed and movable contact structure coacting in said casing, said fixed contact structure being rotatably mounted in said casing about its longitudinal axis and having contact surfaces spaced with respect to each other along said axis, said contact surfaces being angularly spaced about said axis, and stationary contacts mounted in said casing 20 arranged to be selectively engaged by said contact surfaces, respectively, for selectively connecting said fixed contact structure to alternative busbar connections.
- 25 2. A bus-bar selection device and circuit breaker for use with multiple bus-bar metal-clad high tension switchgear including alternative stationary bus-bar connections comprising a member rotatable about its longitudinal axis and carrying the fixed contact structure of the circuit breaker, and having contact surfaces spaced from one another along its axis, the contact surfaces being angularly spaced about the axis and being adapted to be brought into engagement successively with said stationary connections associated with the bus-bars on rotation of the member.
- 35 3. A combined bus-bar selection device and circuit breaker for use with metal-clad switchgear comprising an elongated casing supporting spaced plug type contacts adapted to be brought into

engagement with coacting contacts on a stationary structure carrying bus-bars connected each to one of the said coacting contacts, a member mounted so as to be rotatable about its axis within the casing, the mounting being arranged so that the member is insulated from the casing, a fixed-circuit breaker contact carried at the upper end of said member and adapted to be engaged in the closed position of the breaker by a contact rod movable axially within the casing, said contact rod slidably engaging in its passage to the fixed contact a contact connected to one of said plug-type contacts and contact elements arranged on said rotatable member in spaced relation along the axis thereof and angularly spaced about 15 said axis, the contact elements being disposed to be brought selectively into engagement with one of the remaining plug type contacts on rotation of the rotatable member.

4. A combined bus-bar selector and circuit breaker as claimed in claim 3, in which the fixed contact is within an explosion pot which provides 20 control on breaking circuit.

5. A combined bus-bar selection device and circuit breaker for use with metal clad switchgear comprising a casing, relatively fixed and movable contacts coacting within said casing, an insulator mounted in said casing for rotation about its longitudinal axis, said insulator supporting said fixed contact and provided with a 25 pair of contacts spaced with respect to each other along said longitudinal axis and angularly spaced about said axis, the aforesaid contacts electrically connected to said fixed circuit breaker contact, and three exterior circuit connections 30 mounted in said casing, one of said connections being electrically connected to said movable contact and the other two of said connections arranged alternatively to coact with said angularly spaced contacts so that rotation of said insulator 35 is effective selectively to connect said fixed circuit breaker contact to said alternative connections.
